Des. 189,332
Patented Nov. 22, 1960

189,332

SANDWICH COCKTAIL PICK

Harold Silver and Howard Black, New York, N.Y., assignors to Albert Solton, Haddonfield, N.J.

Filed Oct. 23, 1957, Ser. No. 48,213

Term of patent 3½ years

(Cl. D86—10)

We claim:

The ornamental design for a sandwich cocktail pick, as shown.
